APPARATUS FOR THREADING STRIP
 George W. Hegel, Shelbyville, and Carl E. Tomaszewski,
 Fairland, Ind., assignors to General Electric Company,
 a corporation of New York
 Filed Mar. 28, 1961, Ser. No. 98,844
 5 Claims. (Cl. 263—3)

This invention primarily relates to a vertical or tower type furnace for the treatment of metal strip wherein the strip is drawn in at the bottom, traversing along a vertical path to the top of the furnace and after passing over a strip guide roll is returned to the bottom of the furnace along a second vertical path. More particularly, this invention relates to such a furnace incorporating apparatus for threading or rethreading the metal strip through the furnace without the loss of or contamination of the special atmosphere within the furnace.

In the heating and cooling of strip metal for metallurgical and manufacturing purposes, it is frequently necessary to provide a furnace having a treating chamber which is substantially sealed with respect to the ambient atmosphere. A special gas or mixture of gases is then provided to afford a special atmosphere in the treating chamber in order to obtain or retain the desired properties in the strip metal being treated, and in some instances such an atmosphere must be very pure and dry so that the strip metal being treated is not subject to the serious oxidation to which it is more susceptible at elevated temperatures. In some processes, hydrogen or dissociated ammonia atmospheres of a very high purity and having a dew point of the order of -60° F. are utilized. Since such furnaces are normally lined with fire brick which readily absorb moisture, it is apparent that if any ambient atmosphere is permitted to enter the furnace it will be absorbed by the lining of the furnace and contaminate the protective atmosphere of the treating chamber. Because of the adverse effect on any strip metal which is treated in the furnace prior to the elimination of the moisture in the lining, it is apparent that the furnace must be decontaminated prior to use if ambient atmosphere enters the treating chamber. This may take as long as eight hours or more, and thus a serious loss of production time occurs.

Moreover, since the strip must be threaded over the strip guide roll positioned in the top of the furnace, it has been the normal practice to gain access to the furnace through an access opening in the top of the furnace above the strip guide roll and dropping the two ends of a chain down opposite sides of the guide roll so that the center of the chain rests on the guide roll and one of the ends of the chain can be connected to the end of the strip metal being threaded into the furnace. The strip metal may then be rethreaded through the furnace over the guide roll by pulling the other end of the chain. It will be readily apparent that, due to the high temperature in the furnace which, in some processes, may be as high as 2100° F., there is a problem of safety and comfort on the part of the personnel who engage in the opening of the access port in the top of the furnace for the rethreading of the strip metal. In addition, in a number of processes, the special atmosphere within the furnace may, when combined in the proper proportion with external air, form an explosive mixture if the temperature is at the proper level. Accordingly, it is apparent that it would be advantageous to provide apparatus such as that contemplated by the present invention which will permit the threading or rethreading of the furnace without causing any contamination of the special atmosphere within the furnace by the ambient atmosphere.

It is the principal object of this invention, therefore, to provide a vertical tower or furnace incorporating a rela-

2

tively inexpensive apparatus to thread strip metal through the furnace without causing the contamination of the special atmosphere within the furnace by the influx of the surrounding atmosphere.

In accordance with one aspect of this invention, an enclosed threading chamber is mounted on top of the furnace and is sealed with respect to the furnace housing. A sliding gate valve, which is normally in a closed position, isolates the interior of the furnace from the threading chamber. The enclosed threading chamber contains a storage drum about which a threading chain is wrapped in a special manner. If threading or rethreading of the furnace becomes necessary, the sliding gate valve is opened to provide communication between the interior of the threading chamber and the interior of the furnace. The threading chain is wrapped on the drum in the enclosed threading chamber in such a manner that, upon rotation of the storage drum in one direction, two ends of the chain will unwind simultaneously and lower on opposite sides of the strip guide roll until the chain is released completely from the storage drum and rests on the strip guide roll. An end of the strip metal is then secured to one end of the threading chain over the strip guide roll by pulling on the other end of the chain. After the sliding gate valve is closed to isolate the threading chamber from the interior of the furnace, the chain may be rewound on the storage drum of the threading apparatus for subsequent use through an access port in a wall of the threading apparatus. After the chain is in place for the next threading operation, the access opening is closed and the enclosed apparatus purged of air before the next use.

For a better understanding of the present invention, together with other and further objects and advantages thereof, reference is made to the following description taken in conjunction with the accompanying drawings in which like reference numerals on the several figures identify like parts. The features of novelty which characterize this invention are set forth in the appended claims.

FIGURE 1 is a partial cross-sectional view of the upper section of the furnace embodying the preferred embodiment of this invention;

FIGURE 2 is a top view of a sliding gate valve utilized in the invention;

FIGURE 3 is a side view taken from lines 3—3 of FIG. 2 and illustrates the sliding gate valve in a closed position; and

FIGURE 4 is an isometrical view of the chain storage drum of this invention.

Referring now to the drawings, this invention is shown as applied to a vertical or tower type furnace 10. The furnace 10 is provided with walls 11 which are substantially air tight. As shown, the furnace 10 is provided with a heating chamber 12 which is lined with fire brick 13. The heating chamber is provided with a source of heat which may be in any suitable form, such as molybdenum electrically-energized heating elements (not shown). The upper portion of the heating chamber is isolated from the chamber containing the strip guide roll 28 by a horizontal wall 14 having a slot 15 therethrough for the passage of the strip from the drum to the heating chamber. This horizontal wall 14 serves as a radiation and heat shield to prevent the overheating of the strip guide roll 28.

The fire brick 13, being porous in nature, will, if subjected to moisture, readily absorb the moisture. Therefore, on the initial starting of the furnace and thereafter if the special atmosphere is contaminated with moisture, it is necessary to heat the fire brick for a period of eight hours or longer so that the fire brick is dried out so that it does not serve as a source of moisture to raise the dew point of the atmosphere within the furnace to an unsatisfactory level, thereby increasing the oxidation of the strip

being treated within the furnace at elevated temperatures.

The furnace also provides a vertical channel 16 through which the strip passes before passing over the strip guide roll 28.

The furnace is further provided with the threading apparatus 21 of this invention. The threading apparatus is mounted on the top of the furnace housing in sealed relation therewith and is positioned vertically above strip guide roll 28, as best shown in FIG. 1. A sliding gate valve 23 is positioned between the threading apparatus 21 and the top of the furnace housing and when opened provides communication between the isolating chamber 24 formed by the walls of the threading apparatus 21 and interior of the chamber 25 which contains strip guide roll 23 through opening, or port, 26 in the top wall of furnace 10.

When rethreading of strip metal through furnace 10 becomes necessary, the gate valve 23 is opened by withdrawing valve handle 27, as indicated by the dotted line 27a in FIG. 2. This provides communication between isolating chamber 24 containing the rethreading chain, or similar rope-like member, and chamber 25 of furnace 10 through opening 26. The threading chain 29 having weights 30 attached to its opposite ends and wound on the drum 31 in two spaced spools respectively defined by disks 32, 33 and 34, 35 is then unwound by turning crank 36.

As shown in FIG. 1, the axis of drum 31 is positioned substantially at right angles with respect to the axis of strip guide roll 28. Also the longitudinal center of drum 31 is positioned substantially vertically from the center line of strip guide roll 28. Thus, with the opposite ends of the chain 29 being wrapped on the two spaced spools formed by disks 32, 33 and 34, 35 respectively, it is apparent that upon lowering the weights 30 by turning crank 36, the pair of weights 30 will be located on opposite sides of the vertical center line of strip guide roll 28 so that chain 29 will straddle strip guide roll 28.

When the crank 36 is turned to completely unwind the chain from storage drum 31, the chain 29 will be completely released from the storage drum 31 when the slots 37 and 38 (as best illustrated in FIG. 4) of disks 33 and 34 respectively are positioned in a vertically downward position. The chain 29, therefore, comes to rest on top of the strip guide roll 28 in the position shown in the dashed lines of FIG. 1.

It will then be apparent that the metal strip may be secured to one end of chain 29 and rethreaded through the furnace over the top of strip guide roll 28 by pulling on the other end of the chain, thus completing the rethreading operation of furnace 10 without opening the interior of the furnace 10 to the ambient atmosphere.

The reloading of the chain 29 on the storage drum 31 in preparation for the next rethreading operation may be accomplished without contaminating the special atmosphere within the furnace 10. To accomplish this, the gate valve 23 is placed in a closed position, as shown in FIG. 3, and access port 40 in a wall of threading apparatus 21 is opened. The chain 29 may then be wound on drum 31 by positioning the center portion of the chain in slots 37 and 38 of disks 33 and 34 respectively and turning crank 36 so as to wrap the chain on the two spools formed by disks 32, 33 and 34, 35 respectively so that the chain assumes the position shown in FIG. 1. The access port 40 may then be closed and resecured and the air purged from the isolating chamber 24 of the rethreading apparatus 21 so that it is ready for the next threading operation.

While there has been illustrated and described what is considered at present to be the preferred embodiment of this invention, it will be obvious to those skilled in the art that various changes and modifications may be made thereto without departing from the spirit and scope of this invention. It is therefore to be understood that it is intended that the appended claims cover all such

changes and modifications that fall within the true spirit and scope of this invention.

What we claim as new and desire to secure by Letters Patent of the United States is:

- 5 1. A vertical tower having means defining a pair of vertical paths for the movement of strip therethrough, a strip guide roll positioned adjacent the top of said tower and positioned between said pair of vertical paths for the transfer of strip from one of said paths to the other, and means for threading the strip over said strip guide roll without causing contamination of the atmosphere within the tower by ambient atmosphere, said threading means comprising an enclosed isolating chamber positioned above said strip guide roll and sealed with respect to the top of said tower, means defining an opening in the top of said tower, valve means for said opening which, when opened, provides communication between said isolating chamber and the interior of said tower, means for storing a rope-like member within said isolating chamber, and means for releasing the rope-like member from its stored position to a position straddling said drum whereby strip may be threaded over said strip guide roll by connecting one end of the rope-like member to an end of the strip and applying a pulling force to the other end.
- 10 2. A vertical tower having means defining a pair of vertical paths for the movement of strip therethrough, a strip guide roll positioned adjacent the top of said tower and positioned between said pair of vertical paths for the transfer of strip from one of said paths to the other, and means for threading the strip over said strip guide roll without causing contamination of the atmosphere within the tower by ambient atmosphere, said threading means comprising an enclosed isolating chamber positioned above said strip guide roll and sealed with respect to the top of said tower, means defining an opening in the top of said tower, valve means for said opening which, when opened, provides communication between said isolating chamber and the interior of said tower, means for storing a rope-like member within said isolating chamber having a spindle about which a rope-like member may be wound in such a manner that both ends will unwind from the spindle simultaneously, and means for directing the ends of said rope-like member on opposite sides of the strip guide roll so that the rope-like member when released from said storage drum straddles said strip guide roll whereby strip may be threaded over said strip guide roll by connecting one end with the rope-like member to the end of the strip and applying a pulling force to the other end.
- 15 3. A vertical tower having means defining a pair of vertical paths for the movement of strip therethrough, a strip guide roll positioned adjacent the top of said tower and positioned between said pair of vertical paths for the transfer of strip from one of said paths to the other, and means for threading the strip over said strip guide roll without causing contamination of the atmosphere within the tower by ambient atmosphere, said threading means comprising an enclosed isolating chamber positioned above said strip guide roll and sealed with respect to the top of said tower, means defining an opening in the top of said tower, valve means for said opening which, when opened, provides communication between said isolating chamber and the interior of said tower, a storage drum having a spindle and a pair of sets of spaced-apart disks on said spindle to respectively provide winding spools adjacent both ends of said spindle and about which a rope-like member may be coiled so that both ends are payed out simultaneously from said storage drum, the axis of said storage drum being positioned substantially 90° with respect to the axis of said strip guide roll, and means for rotating the spindle of said storage drum to release the rope-like member from its stored position to a position straddling said strip guide roll, whereby strip may be threaded of said strip guide roll by connecting one end of the rope-like member to one end of the strip.
- 20 4. Apparatus as claimed in claim 3 in which the in-
- 25 50 30 35 40 45 50 55 60 65 70

ner disk of each of set of disks is provided with a radial slot to release the rope-like member from the storage drum when the slot is in a substantially downward direction.

5. A vertical type heat treating furnace having a treating chamber which is substantially sealed with respect to the ambient atmosphere and defining a pair of vertical paths for the movement of strip therethrough, a strip guide roll positioned adjacent the top of said furnace and positioned between said pair of vertical paths for the transfer of strip from one of said paths to the other, means defining an opening in the top of said furnace above said strip guide roll, and means for threading the strip over said strip guide roll without contaminating the atmosphere within the furnace, said threading means comprising an enclosed isolating chamber positioned above

said strip guide roll and covering said opening in the top of said furnace, valve means positioned over said opening for providing communication between said isolating chamber and the interior of said furnace, means for storing a rope-like member within said isolating chamber and means for releasing said rope-like member from its stored position to a position straddling said strip guide roll so that strip may be threaded over said strip guide roll by connecting one end of the strip to said rope-like member, and an access port in an external wall of said threading means for storing said rope-like member in said isolating chamber.
